(57) **CLAIM**

The ornamental design for a buckle, as shown and described.

DESCRIPTION

FIG. 1 is an isometric view of a top, rear, and left side of an ornamental design for a buckle;

FIG. 2 is a left side elevational view of the buckle of FIG. 1;

FIG. 3 is a right side elevational view of the buckle of FIG. 1;

FIG. 4 is a front elevational view of the buckle of FIG. 1;

FIG. 5 is a rear elevational view of the buckle of FIG. 1;

FIG. 6 is a top plan view of the buckle of FIG. 1; and,
FIG. 7 is a bottom plan view of the buckle of FIG. 1.
The dash-dash-dash lines are included for the purpose of
illustrating portions of the buckle that form no part of the
claimed design. The dash-dot-dash lines are included for the
purpose of illustrating boundary lines and form no part of the
claimed design.

1 Claim, 7 Drawing Sheets
